DESIGN FOR A CASE FOR A DOOR LOCK

Samuel Oxhandler, Flushing, N. Y., assignor to Sargent & Company, New Haven, Conn., a corporation of Connecticut

Application November 17, 1943, Serial No. 111,713

Term of patent 3½ years

To all whom it may concern:

Be it known that I, Samuel Oxhandler, a citizen of the United States, residing in Flushing, in the county of Queens and State of New York, have invented a new, original, and ornamental Design for a Case for a Door Lock, of which the following is a specification, reference being had to the accompanying drawing, forming part thereof, in which

Fig. 1 is a top plan view of a case for a door lock showing my new design;

Fig. 2 is a side elevational view of the same; and

Fig. 3 is an end view of the lock case looking in the direction of the arrows 3—3 on Fig. 2.

I claim:

The ornamental design for a case for a door lock, substantially as shown.

SAMUEL OXHANDLER.
